UNITED STATES PATENT OFFICE

109,740

DESIGN FOR A LIGHTING FIXTURE OR SIMILAR ARTICLE

Lemuel L. Stewart, Chicago, Ill., assignor to The Adlake Company, a corporation of Illinois

Application May 10, 1937, Serial No. 69,261

Term of patent 14 years

To all whom it may concern:

Be it known that I, Lemuel L. Stewart, a citizen of the United States of America and a resident of Chicago, county of Cook, and State of Illinois, have invented a new, original, and ornamental Design for a Lighting Fixture or Similar Article, of which the following is a specification, reference being had to the accompanying drawing, forming a part thereof, wherein

Fig. 1 is a perspective view of a lighting fixture or similar article, showing my new design;

Fig. 2 is a vertical, sectional view taken on the line 2—2 of Fig. 3; and

Fig. 3 is a bottom plan view.

The dominant features of my design reside in the parts shown in solid lines.

I claim:

The ornamental design for a lighting fixture, or similar article, substantially as shown, and described.

LEMU^E L. STEWART.
